UNITED STATES PATENT OFFICE.

FREDERICK ERNEST JANSCHKE, OF HATBORO, PENNSYLVANIA.

DESIGN FOR A STOCKING.

Application filed November 23, 1928. Serial No. 28,995. Term of patent 14 years.

To all whom it may concern:

Be it known that I, FREDERICK ERNEST JANSCHKE, a citizen of the United States, residing at Hatboro, in the county of Montgomery and State of Pennsylvania, have invented a new, original, and ornamental Design for Stockings, of which the following is a specification, reference being had to the accompanying drawing, forming part thereof.

Figure 1 is a rear elevation of a stocking in position of use showing my design, Figure 2 is a fragmentary side elevation of the stocking flat, and Figure 3 is an enlarged frag-

mentary rear elevation of the stocking stretched out flat showing the heel and high splice decoration of Figures 1 and 2.

The design comprises high splice upwardly spaced decorations placed back to back having converging edges at the top and of reduced width at an intermediate position to give the effect of outside lateral projection above the restriction.

I claim:

The ornamental design for a stocking, as shown and described.

FREDERICK ERNEST JANSCHKE.
